UNITED STATES PATENT OFFICE.

CHARLES MARIUS MOTTE, OF PARIS, FRANCE.

PROPELLER FOR VESSELS.

Application filed March 22, 1921. Serial No. 454,570.

To all whom it may concern:

Be it known that I, CHARLES MARIUS MOTTE, a citizen of the French Republic, residing at Paris, France, have invented new and useful Improvements in Propellers for Vessels, of which the following is a specification.

My invention relates to propellers for vessels of the kind described in my Patent No. 1,408,765, wherein I have described a turbine for actuating or stopping a vessel without changing the continued rotation of the turbine shaft, this latter comprising a suspended casing which can turn and completely surrounding it; said casing is provided with inlet ports both upper and lower and with a lateral outlet and is controlled by hand operated mechanism independent of the mechanism for actuating the internal vanes of the turbine.

The object of the present invention which is described in detail and hereinafter claimed, is to provide elevated driving power so that the turbine can be used on large vessels.

For this purpose there has been provided a double superposed turbine enclosed in separate casings and provided with appropriate control mechanism co-acting together as shown in the enclosed drawings, in which:—

Figure 1 is a vertical section of a double turbine and of its mechanism; Fig. 2 is an elevation showing an installation comprising several turbines; Figs. 3, 4 and 5 are diagrammatic views showing in plan several positions of the outlet for the water from the turbine casings.

In each of the double superposed turbines, the casing of the upper turbine a encloses a turbine wheel b while the lower casing a^1 surrounds a similar wheel b^1 . The wheel b^1 is fast on a vertical control shaft c turning appropriately in a suspension sleeve d which can turn; to this sleeve is secured the casing a^1 comprising an inlet a^2 and a lateral exhaust a^3 .

The casing a^1 is closed at a^4 and has a flange a^5 to take the lower open extremity of the casing a which has an inlet a^6 and a lateral outlet a^7 . The wheel b is secured to a tubular shaft e turning appropriately and lodged in an external sleeve f which holds suspended the casing a . Guiding means g and h for the sleeve f are provided where desired.

The control shaft i and a bevel wheel i^2 give movement to the wheels b and b^1 . A casing j vertically adjustable by means of a screw-threaded stem j^1 and a handwheel j^2 , encloses the said control mechanism which is operated by a motor k through bevel gear k^1 and i^2 . Uprights or standards l hold the mechanism in the adjusted position.

In order to allow the raising and lowering of the propelling mechanism without disengaging it from the motor, the bevel gear k^1 , which is in engagement with the wheel i^2 fast on the shaft i , is mounted, by means of a Cardan joint, at one end of a horizontal shaft which carries at its other end of a second Cardan joint which connects it with the motor shaft k .

This intermediate horizontal shaft, has two Cardan joints forming the flexible connection between the motor and the propelling mechanism and transmits to the latter the rotary movement of the motor while also allowing of the vertical adjustment by means of the stem j^1 and the handwheel j^2 , the bevel gear i^2 and k^1 being always in mesh no matter what the position (high or low) of the turbines may be.

In order to turn or rotate the water outlet orifices a^3 and a^7 to any angular position, a direction controlling mechanism is indicated, it consisting of a control shaft m which turns a shaft n on which is secured a long toothed pinion n^1 .

When the propeller comprises only a single superposed group of elements arranged in the vertical axis of the vessel as in Fig. 1, the pinion n^1 acts through the intermediary of a pinion wheel, with a toothed wheel o just on the hollow shaft d of the lower casing a^1 and by means of two intermediary pinions, with a second tooth wheel p fast on the hollow shaft f of the upper casing a . In this manner, there obtains, by the rotation of shaft m , the angular displacement of the casings a and a^1 in opposite directions to each other their outlet orifices being able to take up all the positions indicated in Figs. 3 to 5 to propel or stop the boat.

In the case where the propeller comprises two superposed groups of elements, symmetrically disposed at each side of the vertical axis of the vessel as in Fig. 2, the toothed wheels o and p , integral with the hollow shafts of the casings a and a^1 , each mesh with a single intermediate pinion in gear with the long pinion n^1 . The super-

posed casings a and a^1 of each group turn therefore in the same direction and through their respective control shafts can turn in opposite direction to those of the other group.

I claim:

Means for propelling and stopping vessels consisting in suspended and superposed tur-

bine casings, upper and lower inlet orifices and a lateral outlet in said casings, means for suspending said casings and means for simultaneously turning same and mechanism for transmitting power for continuously rotating the turbine wheels.

CHARLES MARIUS MOTTE.
